UNITED STATES PATENT OFFICE

2,179,610

BURNER FOR LIQUID FUEL

James L. Breese, Santa Fe, N. Mex., assignor to
Oil Devices, Santa Fe, N. Mex., a limited partnership of Illinois

Original application March 18, 1937, Serial No.
131,573. Divided and this application January
17, 1938, Serial No. 185,284

3 Claims. (Cl. 158—91)

My invention relates to an improvement in burners and is particularly adaptable to burners or stoves or furnaces burning liquid hydrocarbon and the like.

5 One purpose is the provision of improved baffle means.

Another purpose is the provision of improved means for adjusting the baffle, the baffles being employed for controlling combustion or limiting 10 down drafts of air in the so-called pot type of burner.

Other objects will appear from time to time in the course of the specification and claims.

The present application is a division of my co-pending application Serial No. 131,573, filed on 15 the 18th day of March, 1937.

I illustrate my invention more or less diagrammatically in the accompanying drawing wherein:

Figure 1 is a vertical axial section;

20 Figure 2 is a section on the line 2—2 of Figure 1; and

Figure 3 is a vertical axial section through a variant form of the device.

Like parts are indicated by like characters 25 throughout the specification and drawing.

Referring to the drawing, 1 indicates any suitable base or surface upon which I indicate as supported an outer shell or housing 2. 3 indicates an inner housing or shell having about its 30 base a plurality of air apertures 4. It will be understood that any suitable means may be employed for admitting air to the space between the members 2 and 3.

5 5 is any suitable horizontal or transverse partition adjacent the bottom of the member 3 and herein shown as above the level of the air inlet apertures 4. It may be provided with a central aperture 6 herein shown as closed by the apertured or foraminous plate 7. 8 is an inlet pipe 40 for a liquid fuel and 9 generally indicates a fire pot, combustion chamber or mixing chamber through the bottom 10 of which extends the outlet end 11 of the fuel pipe 8.

12 indicates a bottom row of apertures whereby air may penetrate to the interior of the member 9. 13 indicates other apertures, the apertures 12, or the apertures 12 and 13 together, being effective to admit a primary air supply for mixture with the vaporized liquid hydrocarbon 50 which spreads out on the bottom 10 and is fed from the fuel pipe 8. 14 indicates an upper group or row of air apertures herein shown as upwardly and inwardly inclined. These apertures are adapted to admit a secondary air supply 55 which, when it minglest with the vaporized

hydrocarbon which is already mixed with the air from the primary air inlets 12 and 13, forms the combustible mixture the full combustion of which takes place above the upper edge of the pot or chamber 9.

5 In Figure 1 I illustrate this chamber as partially closed by an upper baffle 15 with a central aperture 16. In order to control or vary the effective diameter of the aperture in the baffle 15, I provide a rotatable ring 17 having any suitable 10 control handle or member 18 and being provided with a plurality of arcuate slots 19 of predetermined length. These slots 19 receive headed members 20 which may be mounted upon the baffle 15.

15 The ring 17 is the actuating member for the iris diaphragm structure formed of a plurality of shutter members 21, each of which is pivoted as at 22 to any suitable abutment ring 23 shown as mounted upon the baffle 15. Each member 21 is also provided with a slot 24 in which rides a pin or abutment 25 which is mounted on and moves with the ring 17. Each member 21 has an effective inner edge 26.

20 The parts are so proportioned that when the handle 18 is moved to move the ring 17 to one limit of its possible movement the aperture X is practically closed or has any predetermined diameter. When the handle 18 is moved in the opposite direction the members 21 are rotated 30 outwardly in such fashion that their edges 26 define an aperture which may be as great as the aperture 16. In other words, what I provide is in effect a baffle with an adjustable aperture.

25 It will be understood of course that by a mere change in the size and proportion of parts I might so dispose my iris structure as to enable the user to run without a baffle at all if desired. However, I find it preferable to employ the structure as shown in Figures 1 and 2.

35 In Figure 3 I illustrate the baffle structure as located below the secondary air apertures 14, whereas in the form of Figure 1 I illustrate it as above the said apertures. It will be understood that the above described baffle structure 45 may be located at any desired point in the pot 9. When it is located below the apertures 14 I prefer to employ an additional upper baffle 30 with its central aperture 31 whereby to prevent undesired and disadvantageous down drafts from the 50 heating compartment above the pot.

40 It will be realized that whereas I have described and illustrated a practical and operative device, nevertheless many changes may be made in the size, shape, number and disposition of 55

parts without departing from the spirit of my invention. I therefore wish my description and drawing to be taken as in a broad sense illustrative or diagrammatic rather than as limiting me to the precise showing.

5 The use and operation of my invention are as follows:

10 My invention may be broadly applied to any situation where the combustion or mixing chamber is provided with an upper or intermediate baffle having an aperture the diameter of which should be varied or controlled, either at the time of starting combustion in the device or in order 15 to control the rate of combustion or the quality of combustion in the area below the baffle.

15 One application of my invention is to a mixing and combustion chamber in which the primary air supply is first mixed with a hydrocarbon delivered along the line 8 in order to form 20 a preliminary mixture which in turn has supplied to it a secondary air supply in order to create a final and fully combustible mixture. Once combustion is instituted above the bottom 25 of the pot 9, the hydrocarbon delivered along the line 8 is vaporized as a result of such combustion and rises upwardly in the pot 9 and receives the air delivered to it through the apertures 12 and 13. The size and area and distribution of these apertures is so proportioned 30 as to provide sufficient air for a preliminary mixture without providing sufficient air for final combustion. As the mixture rises it receives its final air from the apertures 14 and the completed mixture passes upwardly through the baffle 15 35 in Figure 1, or through the baffle 30 in Figure 3, and combustion takes place in the main above said baffles.

40 It will be realized that my invention includes the employment of means for varying the cross sectional area of the upper opening for the combustion or mixing chamber 9 or for varying the opening of the intermediate or lower baffle.

I claim:

1. In combination, a fuel mixing and combustion chamber for liquid hydrocarbon burners, said chamber having a wall penetrated by a plurality of air inlet apertures, a baffle associated with said chamber and located above the highest of said air inlet apertures, said baffle having an aperture adapted to permit the upward flow therethrough of gases from said chamber, and means for varying the cross sectional area of said aperture and for thereby controlling the inflow of air through said apertures in said chamber wall.

2. In combination, a fuel mixing and combustion chamber for liquid hydrocarbon burners, said chamber having a wall penetrated by a plurality of primary air inlet apertures, an additional row of secondary air inlet apertures adjacent the upper edge of the chamber, a baffle associated with said chamber and located above the highest of the primary air inlet apertures, said baffle having an aperture adapted to permit the upward flow therethrough of gases from the part of the chamber below said baffle, and means for varying the cross sectional area of said aperture, and for thereby controlling the inflow of air through the primary air apertures in said chamber wall.

3. In combination, a fuel mixing and combustion chamber for liquid hydrocarbon burners, said chamber having a wall penetrated by a plurality of air inlet apertures, a baffle associated with said chamber and located adjacent the top of said chamber, said baffle having an aperture adapted to permit the upward flow therethrough of gases from said chamber, and means for varying the cross sectional area of said aperture and for thereby controlling the inflow of air through the apertures in said fuel chamber wall below said baffle.

JAMES L. BREESE. 40
